[57] CLAIM

The ornamental design for an arm elevator, substantially as shown and described.

DESCRIPTION

FIG. 1 is a left front perspective view of an arm elevator, showing my new design;

FIG. 2 is a left side elevational view thereof;

FIG. 3 is a top plan view thereof;

FIG. 4 is a front elevational view thereof;

FIG. 5 is a right side elevational view thereof;

FIG. 6 is a rear elevational view thereof;

FIG. 7 is a bottom plan view thereof.

The broken line disclosure in FIG. 1 is for illustrative purposes only and forms no part of the claimed design.
